Application September 2, 1949, Serial No. 4,826

Term of patent 14 years

(Cl. D34—11)

To all whom it may concern:

Be it known that I, Alfred E. Maage, Jr., a citizen of the United States, residing at Milwaukee, in the county of Milwaukee and State of Wisconsin, have invented a new, original, and ornamental Design for a Coin Actuated Calendar Bank, of which the following is a specification, reference being had to the accompanying drawing, forming a part thereof.

In the drawing:

Figure 1 is a perspective view of a coin actuated calendar bank, showing my new design;

Figure 2 is a top plan view of the coin actuated calendar bank shown in Figure 1; and

Figure 3 is a right side elevational view of the coin actuated calendar bank shown in Figure 1.

I claim:

The ornamental design for a coin actuated calendar bank, as shown.

ALFRED E. MAAGE, JR.
